AUTOMATIC SAFETY VALVE

Robert M. De Lawter, Anderson, Ind.

Application April 15, 1935, Serial No. 16,463

4 Claims. (Cl. 137—153)

This invention relates to certain new and useful improvements in automatic safety valves.

The primary object of the invention is to provide a valve structure in a fluid line, such as gas or liquid, with the valve having a diaphragm associated therewith and held in an open position with respect to its seat by the pressure of fluid flowing through the line and valve and constructed for automatically closing on its seat 5 should the pressure in the line and valve fall to a predetermined point and being operated to remain seated upon the rise of pressure in the line.

A further object of the invention is to provide an automatic safety valve of the foregoing character embodying valve and diaphragm chambers with longitudinal ports in the valve stem forming communication between the valve and diaphragm chambers for acting on one face of the diaphragm to elevate the same and hold the valve unseated for the normal flow of fluid through the valve chamber, the valve automatically closing on its seat in the presence of a drop in pressure in the valve chamber with a lessened pressure than flowing through a port in the valve stem to 20 act on the other face of the diaphragm for maintaining the valve on its seat.

A still further object of the invention is to provide a valve of the foregoing character especially designed for association with a gas service pipe 30 or in an oil supply pipe for oil burners to prevent explosions, fires and asphyxiation should the usual pilot light become extinguished in the presence of a reduction in fluid pressure with the valve automatically closed on its seat during such reduction in pressure and then remaining closed 35 when the pressure is raised or restored.

With the above and other objects in view that will become apparent as the nature of the invention is better understood, the same consists in 40 the novel form, combination and arrangement of parts hereinafter more fully described, shown in the accompanying drawing and claimed.

In the drawing:—

Figure 1 is a longitudinal sectional view of the 45 automatic safety valve with the valve raised from its seat and so maintained by fluid pressure acting on one face of a diaphragm carrying the valve;

Figure 2 is a longitudinal sectional view of the 50 device showing the valve closed on its seat and so maintained by fluid pressure acting on the other face of a diaphragm associated with the valve; and

Figure 3 is a side elevational view of the key 55 employed for manually unseating the valve.

Referring more in detail to the accompanying drawing, there is illustrated an automatic safety valve comprising valve and diaphragm casings 5 and 6 secured together as at 7. The connection between the valve and diaphragm casings comprises a central opening 8 in the top wall of the valve casing 5 and the bottom wall of the diaphragm casing 6 is provided with a central opening surrounded by an upstanding flange 9 and a bottom wall 10 that extends into the opening 10 5 in the top wall of the valve casing with a central opening 11 in the bottom wall 10.

A valve stem 12 is slidably mounted through the opening 11 in the bottom wall 10 of the diaphragm casing 6 and carries a valve 13 at its 15 lower end for engagement with the valve seat 14 in the partition 15 in the valve casing 5. Packing material 16 is interposed between the valve stem 12 and flange 9, being engaged with the bottom wall 10 and is retained in position by the 20 packing gland 17 threaded into the flange 9, to form a fluid tight strip for the valve stem. A diaphragm 18 extends between the peripheral edge of the diaphragm casing 6 and the upper end of the valve stem 12 to provide separate chambers 25 19 and 20 in the diaphragm casing, the diaphragm 18 being braced by the disk plates 21 arranged at opposite sides thereof and anchored as at 22 to the upper end of the valve stem.

The longitudinal passage 23 is formed in the 30 valve stem 12 with an angularly extending port 25 at its lower end adjacent the valve 13 and an angularly extending port 26 intermediate the ends of the valve stem, the two ports 25 and 26 opening at the same side of the valve stem and 35 being so related whereby the port 26 registers with the packing 16 when the valve 13 is engaged with its seat 14. A second passage 27 extends longitudinally of the valve stem 12, the upper end 28 thereof opening at the terminal 40 upper end of the valve stem and communicating with the chamber 20 in the diaphragm casing while the lower end of the passage 27 communicates with an angle port 29 above and opposite the port 25, the port 29 registering with the 45 packing 16 when the valve 13 is removed from its seat.

The top wall of the diaphragm casing 6 is provided with a threaded opening in line with the valve stem 12 and is closed by the threaded 50 plug 30. An internally threaded socket 31 is formed in the upper end of the valve stem 12 and is adapted to receive the threaded end 32 of the key 33 shown in Fig. 3 by inserting the key 33 through the opening in the top wall of 55

the diaphragm casing 6 when the plug 30 is removed for the purpose of manually unseating the valve 13.

5 The valve casing 5 has inlet and outlet end connections 34 and 35 respectively. With the valve 13 unseated as illustrated in Fig. 1, fluid passing through the valve casing 5 by-passes through the ports 25, passage 23 and port 26, the valve stem 12 to enter the chamber 19 of the diaphragm casing 6 for engaging the under-
10 side of the diaphragm 18 to exert pressure thereon and to maintain the valve 13 unseated. Should pressure fall below a predetermined degree in the valve casing 5, the valve and dia-
15 phragm gravitationally descend and the valve 13 closes on the seat 14. Should pressure sud-
denly or otherwise arise in the valve casing, the fluid flows through the passage 27 in the valve
20 stem 12 to enter the chamber 20 in the dia-
phragm casing for contacting the upper side of
25 the diaphragm 18 to exert pressure thereon and hold the valve 13 on its seat 14. The pressure
may then rise or fall, but the valve will still re-
main closed upon its seat. To open the valve, it
25 is necessary to remove the plug 30 from the top
wall of the diaphragm casing 6 and use the key
33 shown in Fig. 3 to engage the upper end of
the valve stem for unseating the valve 13.

30 A device of this character is especially service-
able in connection with oil or gas burners for
heating plants and the like which employ pilot
lights so that in the event of fall of pressure
below a predetermined degree, the valve 13 auto-
matically closes on its seat and a sudden or other
35 rise of pressure will fail to unseat the valve but
act to more firmly hold the valve onto its seat,
a manual operation of the valve being required
to effect unseating thereof. It will be noted
that the angle ports 26 and 29 of the passages
40 in the valve stem are so related to the packing
16 as to be respectively registerable therewith
to effect a leak-tight connection or condition when
the valve is either opened or closed for the more
effective operation of the device.

45 From the above detailed description of the
invention, it is believed that the construction
and operation thereof will at once be apparent
and while there is herein shown and described
the preferred embodiment of the invention, it
50 is nevertheless to be understood that minor
changes may be made therein without depart-
ing from the spirit and scope of the invention
as claimed.

I claim:—

55 1. In an automatic safety valve, valve and
diaphragm casings, a valve in the valve casing
having a stem extending into the diaphragm
casing, a diaphragm in the diaphragm casing

connected to the valve stem and forming sepa-
rate chambers therein, the valve stem having
passages therein selectively forming communi-
cation between the valve casing and the separate
chambers for either holding the valve on its seat
or spaced therefrom and a bearing for the valve
stem cooperating with the passages to form clo-
sures therefor. 5

2. In an automatic safety valve, valve and dia-
phragm casings, a valve in the valve casing hav-
ing a stem extending into the diaphragm casing,
a diaphragm in the diaphragm casing connected
to the valve stem and forming separate cham-
bers therein, the valve stem having passages
therein selectively forming communication be-
tween the valve casing and the separate cham-
bers for either holding the valve on its seat or
spaced therefrom, and a packing through which
the valve stem is movable adapted to seal the
idle passage in the valve. 10 15 20

3. In an automatic safety valve, valve and dia-
phragm casings, a valve in the valve casing
having a stem extending into the diaphragm
casing, a diaphragm in the diaphragm casing
connected to the valve stem and forming sepa-
rate chambers therein, a pair of longitudinally
extending passages in the valve stem one of said
passages having angle ports at its ends spaced
from the ends of the valve to form communica-
tion between the valve casing and lower cham-
ber in the diaphragm casing and the other
passage having an angle port at its lower end
and opening at the upper end of the valve to
form communication between the valve casing
and the upper chamber in the diaphragm casing
35 and a bearing for the valve stem cooperating
with the lower end of one passage and the upper
end of the other passage to form a closure
therefor. 30 35

4. In an automatic safety device, valve and dia-
phragm casings, a valve in the valve casing
having a stem extending into the diaphragm
casing, a diaphragm in the diaphragm casing
connected to the valve stem and forming sepa-
rate chambers therein, a pair of longitudinally
extending passages in the valve, one of said
passages having angle ports at its ends spaced
from the ends of the valve to form communica-
tion between the valve casing and lower cham-
ber in the diaphragm casing and the other pas-
sage having an angle port at its lower end and
opening at the upper end of the valve stem to
form communication between the valve casing
and the upper chamber in the diaphragm casing,
and a packing through which the valve stem is
movable adapted to seal the idle passage in the
valve. 40 45 50 55

ROBERT M. DE LAWTER.
